DESIGN FOR A CHAIR OR SIMILAR ARTICLE

Erick Arne Johnson and James De Witt McBride,
Duluth, Minn., assignors of one-fourth to Karl
H. Thorsell, Duluth, Minn.

Application January 11, 1936, Serial No. 60,535

Term of patent 14 years

To all whom it may concern:

Be it known that we, Erick Arne Johnson and James De Witt McBride, both citizens of the United States, residing at Duluth, in the county of Saint Louis and State of Minnesota, have invented a new, original, and ornamental Design for a Chair or Similar Article, of which the following is a specification, reference being had to the accompanying drawing, forming part thereof.

We claim:

The ornamental design for a chair or similar article, as shown and described.

ERICK ARNE JOHNSON.
JAMES DE WITT McBRIDE.
